UNITED STATES PATENT OFFICE.

HARLEY C. MOULTON, OF DORCHESTER, MASSACHUSETTS, ASSIGNOR TO ARBETTER FELLING MACHINE COMPANY, OF BOSTON, MASSACHUSETTS, A CORPORATION OF MAINE.

WORKTABLE FOR SEWING MACHINES.

Application filed October 20, 1919. Serial No. 332,029.

To all whom it may concern:

Be it known that I, HARLEY C. MOULTON, a citizen of the United States, and resident of Dorchester, county of Suffolk, State of Massachusetts, have invented an Improvement in Worktables for Sewing Machines, of which the following description, in connection with the accompanying drawing, is a specification, like characters on the drawing representing like parts.

This invention relates to improvements in work supporting tables for sewing machines and the principal object thereof is to provide a work supporting table which will conveniently support garments of various forms in such a manner that the operator can present them easily to the feed and stitch forming mechanism of the sewing machine.

In the use of sewing machines a great variety of articles are operated upon including relatively small articles of tubular form such as sleeves, trouser bottoms and the like, and larger articles also of tubular and rectangular form such as skirts and coats and various heavy articles of considerable extent which cannot conveniently be placed upon the usual bench which supports the bed plate of the sewing machine.

The present invention contemplates the provision of a supplemental table provided with an extension overhanging the work support which will enable a large portion of the garment or large article which is being operated upon to rest upon the bench while the portion being operated upon is carried over the surface of the work supporting table to the stitch forming mechanism.

A further object of the invention is to provide means for detachably securing the supplemental table to the bed plate of the sewing machine so that it can be removed and the machine operated with the usual work support to stitch small tubular articles and the like.

In sewing various articles it is desirable that the operator may grasp the work in the line of stitching closely adjacent to the needle. Another object of the invention therefore is to provide a work supporting table of the character described with a recess behind the stitching mechanism so that the hand of the operator may be brought down to the level of the work supporting surface of the work support thereby enabling the goods to be guided horizontally past the

stitch forming mechanism, a further advantage residing in the fact that the operator can then rest the elbow upon the bench or bed plate of the machine and guide the work without becoming tired.

Another object of the invention is to provide a novel anchoring means for detachably fastening the supplemental work supporting table to the bed plate of the machine.

Other objects and features of the invention will more fully appear from the following description and the accompanying drawings and will be pointed out in the annexed claims.

A preferred embodiment of the invention is illustrated in the accompanying drawings in connection with a blind stitch sewing machine of the "Arbette" type, but it will be understood that the invention is adapted for use in connection with any other type of sewing machine having a work support extending a distance above the surface of the bed plate.

In the drawings,

Fig. 1 is a side elevation of a sewing machine showing the invention associated therewith,

Fig. 2 is a plan view of the end of the sewing machine bed plate, the work support and the work supporting table embodying my invention associated therewith,

Fig. 3 is a sectional view through the bed plate on lines 3-3 Fig. 1, the work supporting table being shown in elevation,

Fig. 4 is a sectional detail view of a portion of the work supporting table and the bed plate and of one of the locking means which connects the table to the bed plate,

Fig. 5 is a plan view of two sections of the bed plate associated together, showing the positions of the key slots in the bed plate and illustrating in sections the studs carried by the table which engage the key slots and lock the table to the bed plate, and

Fig. 6 is a vertical sectional view on line 6-6.

The sewing machine illustrated in the drawing comprises a bed plate 1 which is secured to a usual bench 2, a standard 3 rising from said bed plate and having an overhanging arm 4 and head 5 carrying the usual stitch forming mechanism. The stitch forming mechanism in a machine of the type illustrated herein comprises an oscillating needle 6 and complementary stitch 110

forming mechanism which may be of any usual character (not shown).

The presser foot 7 carried by the head cooperates with the yieldable work support 8 which is carried by a suitable standard 9 and extends a considerable distance above the surface of the bed plate. This construction may be of a usual type but preferably the work support 8 is carried to a high position above the bed plate and the sewing machine standard 3 is correspondingly extended to provide a larger clearance beneath the arm to receive the material which is operated upon, thereby giving the machine a greater capacity.

The work supporting surface of the work support desirably is relatively small so that small tubular articles such as sleeves may be readily presented to the stitch forming mechanism. When larger articles however are to be operated upon it becomes inconvenient to present them to the stitch forming mechanism and the present invention has been devised for the purpose of providing a suitable and convenient support for articles of any character or size.

The invention broadly comprises a table adapted to be detachably secured to the bed plate of the machine and to present a work supporting surface which will co-operate with the work supporting surface of the work support of the machine, the area of the table being sufficient to support a large amount of the work. The table is also desirably provided with an extension overhanging the bench and providing a sufficient space to enable a large amount of material to rest upon the bench out of the way of the operator.

This is particularly convenient where large tubular articles such as skirts are being stitched for it enables the larger portion of the skirt to rest upon the bench while the portion which is being sewed is carried upon the surface of the table and readily presented to the stitch forming mechanism.

The preferred form of table comprises a stand having a vertical front wall 10 and side wall 11 and a top 12, webs 13 and 14 extending laterally from the side wall 11 and a connecting web 15 forming a strengthening support for an extension 16 of said top. The top 12 is cut away to provide an L-shaped recess 17 to partially surround the work support 8 of the sewing machine. At the rear of the recess the table is provided with a depressed portion, the bottom 18 of which extends downward in a gentle curve from the surface of the table as illustrated in Fig. 1, nearly to the surface of the bed plate. A supporting wall 19 extends from the side wall 11 along the front of the depressed bottom 18. The table thus formed is provided with feet 20 and 21 extending downwardly from the bottom 18 of the de-

pressed portion, and feet 22, 23 formed integral with the front wall 10, the surface of these feet preferably being machined so as to set firmly upon the bed plate of the machine. An L-shaped plate 24 which is suitably secured to the top 12 of the table preferably surrounds the work support 8 and provides a smooth surface, upon which the goods may be manipulated by the operator, closely adjacent to the stitching point.

The depressed portion of the table at the rear of the work support enables the operator to grasp and hold the work horizontally, thereby facilitating the operation of guiding the material past the stitch forming mechanism. This recess also enables the operator more easily to remove and replace the bobbin in machines of the character illustrated in which the rotary hook or looper is carried from a hook bracket depending from the head of the machine.

Any suitable means may be provided for anchoring the work supporting table to the bed plate of the machine. As illustrated herein the bed plate is provided with a plurality of apertures, two as illustrated, which are surrounded by countersunk plates 25, 26 which are secured to the bed plate by suitable screws. These plates have key slot apertures 27 and 28 adapted to receive the heads of anchoring members such as studs carried by the table.

The smaller portion of the key slot apertures preferably converge toward each other and toward the work support so that when the studs are inserted through the apertures and caused to approach toward each other the table will be firmly clamped to the bed plate and drawn to its proper position in relation to the work support.

Any suitable locking means may be used to connect the table to the key slot apertures, a convenient means which is illustrated herein comprises a stud 29 seated in a boss 30 projecting downwardly from the inside of the bottom 18 of the depressed portion of the table, said stud having an enlarged head 31 adapted to pass through the enlarged portion of the key slot but too large to pass through the narrower portion thereof and a co-operating adjustable stud of a similar character.

A preferred form of adjustable stud which is illustrated in detail in Fig. 4 comprises a bar 32 pivotally secured at its upper end upon a stud 33 mounted in suitable bosses 34, 35 extending rearwardly from the front plate 10 and having at its lower end a stem 36 terminating in a head 37 adapted to enter the enlarged portion of the key slot.

The position of the bar 32 may be adjusted by a screw 38 having an end portion 39 of smaller diameter extending through the bar 32 and rotatably secured therein by a screw 40 seated in the bar 32 and en-

gaging in a slot 41 in said screw. The screw threaded portion of the screw 38 extends through a boss 42 upon the front wall 10 and through the wall 10 itself. The 5 head 43 of the screw 38 may be provided with a transverse hole 44 adapted to receive a screw driver or other lever suitable for applying considerable power to the screw.

10 In operating the machine upon small articles the table may be removed and the stitching done upon a machine in the usual manner. When larger articles are to be stitched the table may be associated with 15 the work support of the machine by merely placing the table upon the bed plate in such a manner that the heads 31 and 37 of the studs will pass through the key slot apertures 27 and 28 in the plates 25 and 26, the 20 screw 38 then being set up to cause the pivotally mounted bar 32 to be moved inwardly, thereby forcing it toward the stud 29 and causing the heads 31 and 37 to lock the table firmly to the bed plate of the 25 machine. The operator may then place a part of the work upon the bench, carrying such portion as is to be stitched over the extension 16 and the top 12 of the table to the 30 stitch forming mechanism. When the goods 35 have been presented to the needle, the operator may, by reaching around behind the arm 4 and head 5, grasp the work immediately behind the stitching point and thereby manipulate it much more easily than in usual machines.

It will be understood that the invention illustrated herein is illustrative and that various changes in construction and arrangement of parts may be made within the meaning and scope of the following claims.

Having thus described my invention what I claim as new and desire to secure by Letters Patent is:

1. In combination with a sewing machine 45 comprising a bed plate, an overhanging arm and head, a needle and presser foot carried by said head, stitch forming mechanism, and a yieldable work support located at a distance above said bed plate and co-operating 50 with said presser foot; a work supporting table partially enclosing said work support and having a surface positioned to cooperate with said work support and an extension providing a free space therebeneath 55 whereby a portion of the work may underlie said extension.

2. In combination with a sewing machine comprising a bed plate, an overhanging arm and head, a needle and presser foot carried 60 by said head, stitch forming mechanism, and a yieldable work support located at a distance above said bed plate and co-operating with said presser foot; a work supporting table partially enclosing said work support 65 and having a surface positioned to co-

operate with said work support, an extension providing a free space therebeneath whereby a portion of the work may underlie said extension and means for detachably securing said work supporting table to said bed plate.

3. In combination with a sewing machine comprising a bed plate, an overhanging arm and head, a needle, and presser foot carried by said head, stitch forming mechanism, and 75 a work support located above said bed plate and co-operating with said presser foot; a work supporting table having a surface positioned to co-operate with said work support, an extension providing a free space therebeneath whereby a portion of the work may underlie said extension, said work supporting table having a recess beyond said stitch forming mechanism enabling the operator to grasp the work closely adjacent the stitching 80 point in a plane with the work supporting surface of the work support.

4. A work supporting table, for sewing machines having a work support projecting above the bed plate, comprising a stand having a work supporting surface positioned to 90 co-operate with the work support of the machine and a depressed portion at the rear of the position of the work support enabling the operator to grasp the work close to the 95 stitching point.

5. A work supporting table, for sewing machines having a work support projecting above the bed plate, comprising a stand having a work supporting surface positioned to 100 co-operate with the work support of the machine and a depressed portion at the rear of the position of the work support enabling the operator to grasp the work close to the 105 stitching point and an extension providing a free space therebeneath whereby a portion of the material may be supported beneath said extension while the portion which is being sewed will rest upon the supporting surface of said extension and stand.

6. A work supporting table for sewing machines having a work support projecting above the bed plate comprising a stand presenting a work supporting surface positioned to cooperate with the work support 115 of the machine, co-operating relatively movable anchoring members carried by said stand adapted to engage said bed plate and means for forcing said anchoring members into clamping engagement with said bed 120 plate.

7. A work supporting table for sewing machines, having a work support extending above the bed plate, comprising a stand presenting a work supporting surface positioned to cooperate with the work support of the machine and means for detachably connecting said stand to the bed plate comprising studs having means to engage the bed plate and means for moving one of said 130

- studs relatively to the other whereby said means may be caused to engage complementary means upon the bed plate and clamp said stand firmly thereto.
5. 8. A work supporting table for sewing machines, having a work support extending above the bed plate, comprising a stand presenting a work supporting surface positioned to cooperate with the work support of the machine and means for detachably connecting said stand to the bed plate comprising a stationary and a pivotally mounted stud having enlarged heads adapted to pass through apertures in the bed plate, means 10 for adjusting said pivotally mounted stud toward the stationary stud whereby said studs will be caused to clamp firmly upon the bed plate.
9. A work supporting table for sewing machines, having a work support extending above the bed plate, comprising a stand presenting a work supporting surface positioned to cooperate with the work support of the machine and means for detachably connecting said stand to the bed plate comprising a stationary and a pivotally mounted stud adapted to pass through apertures in the bed plate and an adjusting screw for said pivotally mounted stud adapted to 15 cause said stud in co-operation with the stationary stud to clamp firmly upon the bed plate.
10. A work supporting table for sewing machines, having a work support extending 20 through the bed plate, comprising a stand having a recess to receive said work support, and a finished plate detachably secured to said stand adjacent to and partly sur-
- rounding the work support and presenting a smooth supporting surface for the material adjacent the stitching point.
11. In combination, a sewing machine comprising a bed plate provided with key-slot apertures and a work support projecting above the bed plate, a work supporting table presenting a surface positioned to cooperate with said work support, means for detachably securing said table to said work support comprising studs having stems provided with heads adapted to be inserted through the enlarged portions of the key slot apertures and means for moving one of said studs relatively toward the other to cause the stem to be drawn into the narrow portions of the key slots and the heads thereby caused to clamp the stand upon the bed plate.
12. In combination with a sewing machine comprising a bed plate, and a work support projecting above the bed plate, key slot apertures in said bed plate having the narrow portions converging toward each other and toward said work support, a work supporting table presenting a surface positioned to co-operate with said work support, studs on said table having heads adapted to be inserted through the enlarged portion of said key slots and means for forcing one of said studs toward the other whereby said stand will be clamped to said table and held in proper position relatively to said work support.

In testimony whereof, I have signed my name to this specification.

HARLEY C. MOULTON.
